UNITED STATES PATENT OFFICE.

FREDERICK C. OVERBURY, OF HILLSDALE, NEW JERSEY, ASSIGNOR TO THE FLINT-KOTE COMPANY, OF BOSTON, MASSACHUSETTS, A CORPORATION OF MASSACHUSETTS.

ROOFING.

Application filed April 19, 1919. Serial No. 291,401.

To all whom it may concern:

Be it known that I, FREDERICK C. OVERBURY, a citizen of the United States, residing at Hillsdale, in the county of Bergen and State of New Jersey, have invented new and useful Improvements in Roofing, of which the following is a specification.

In the manufacture of shingles from sheets of prepared roofing material, it is customary, after the sheet has been impregnated with asphalt, pitch or other waterproofing material, then coating it with a layer of higher-melting-point pitch or asphalt, and partially embedding in such coating a layer of grit or crushed mineral, to cut the sheet longitudinally and transversely into shingles of the desired length and width.

The present invention consists of a sheet of roofing in which the shingles are partially formed by longitudinal and transverse interrupted cuts or lines of severance so that the shingles are connected together endwise and sidewise, and the entire sheet may be coiled into a roll or cylindrical package for shipment. The uncut portions or narrow webs, which connect the shingles end to end and side to side, may be easily torn or broken so as to permit the separation of the sheet into individual shingles.

On the accompanying drawing,

Figure 1 illustrates more or less conventionally a machine which may be employed for forming the roofing.

Figures 2 and 3 illustrate the slitting cutters by which the sheet is slit longitudinally by parallel interrupted slits or cuts.

Figures 4 and 5 illustrate the transverse cutters by which the sheet is cut transversely by interrupted cuts or lines of severance.

Figures 6 and 7 illustrate another form of transverse cutting instrumentalities.

Figure 8 shows the sheet with the longitudinal interrupted slits.

Figure 9 shows the sheet after it has been cut transversely and ready to be coiled into a roll.

The machine is illustrated more or less conventionally, and it is provided with the usual feed rolls 10, 10, and with the longitudinal slitting cutters 11, 12. These slitting cutters may be made in any suitable way, as illustrated for example in Figures

2 and 3. They are provided with the registering notches *a b* so as to form the interrupted longitudinal cuts or lines of severance indicated at *c* in Figure 8. The disk-like cutters 11 and 12 are mounted upon shafts 13, 14, and are adjustable lengthwise thereof. After leaving the longitudinal slitting cutters, the sheet passes over a table 15, the end of which is illustrated as forming a stationary shear blade with which cooperates a transversely arranged blade 16 which is notched as at *d* so as to form transverse interrupted cuts or lines of severance indicated in Figure 9 at *e*. The blade 16 is mounted in any suitable form of cross-head or crossbar, which at its ends is secured to movable posts 17, 17, adapted to reciprocate in guides 18 afforded by the frame. Between the guides 18 and the heads of the posts, there are located compression springs 19. Any suitable means may be utilized for reciprocating the cross-head and the transverse blade carried thereby. For example, the shaft 20 may be provided with shoulder cams 21 for engaging shoulders 22 on the posts and momentarily depressing the transverse blade and cross-head. As illustrated, the shaft 20 is driven from a main power shaft 23 by a pinion 24 and gear 25, and from said shaft 20 any suitable form of power-transmitting gearing may be utilized for driving the longitudinal slitting cutters and actuating the feed rolls, such power-transmitting mechanism being indicated more or less conventionally. It is evident that, instead of employing a transverse reciprocating cutter blade, I may employ coacting rotary cutters as indicated in Figures 6 and 7. In this case, the cutter head 26 is provided with notched blades 27 for cooperation with a cutter head 28. The blades 27 are notched as shown in Figure 7.

Preferably the notches are so formed in the longitudinally slitting cutters and the transversely slitting cutters that the potentially formed shingles *f f* all have sharply cut corners. These shingles are laterally connected by narrow webs *g g* and are connected longitudinally by the narrow webs *h*. These webs are of such width that the shingles may be easily separated or torn apart.

After leaving the machine, the sheet of

potentially formed shingles is formed into a roll *k* upon an arbor 29 which is rotated by any suitable means, not shown.

So far as I am aware, I am the first to have provided a roofing package consisting of a roll of sheet material which is slit longitudinally and transversely so as to form a plurality of separable shingles, and I am also the first to have provided such a sheet and means for forming the same.

What I claim is:—

1. A sheet of roofing having angularly disposed rows of spaced slits partially defining roofing units which may be readily

separated, slits of angularly disposed rows 15 intersecting each other to define the corners of the units whereby the production of ragged corners when the units are separated is prevented.

2. A roll of sheet roofing consisting of 20 a coiled sheet of roofing material longitudinally and transversely slit into a plurality of units connected by narrow webs of uncut material intermediate the corners of each unit.

In testimony whereof I have affixed my signature.

FREDERICK C. OVERBURY.
